UNITED STATES PATENT OFFICE.

PETER CLAY, OF SHEBOYGAN, WISCONSIN.

FOLDING BED.

SPECIFICATION forming part of Letters Patent No. 703,545, dated July 1, 1902.

Application filed February 6, 1902. Serial No. 92,894. (No model.)

To all whom it may concern:

Be it known that I, PETER CLAY, a citizen of the United States, and a resident of Sheboygan, in the county of Sheboygan and State 5 of Wisconsin, have invented certain new and useful Improvements in Folding Beds; and I do hereby declare that the following is a full, clear, and exact description thereof.

My invention has especial reference to the 10 construction, arrangement, and operation of the legs connected to the adjustable portion of a folding bed; and it consists in certain peculiarities of construction and combination of parts, as will be fully set forth hereinafter 15 in connection with the accompanying drawings and subsequently claimed.

In the said drawings, Figure 1 is a view in side elevation, representing a folding bed in position for use and showing my improved 20 leg adjusted to support the bed in this position. Figs. 2, 3, 4, and 5 are detail views, drawn to an enlarged scale, illustrating the said leg in different positions, together with the adjacent parts.

Referring to the drawings, *a* represents the 25 cabinet within which the bed is folded; *b*, the base of the bed proper, which forms the front of the cabinet when the bed is folded therein, and *c* one of the side rails of the bed rigidly 30 secured to the base *b*. The bed is supported within the cabinet in any of the well-known ways, this forming no part of my present invention. Adjacent to each corner of the upper or outer end of the bed is a stop *d*, preferably in the form of an angle-piece, one 35 flange of which is secured, as by screws *e e*, to the inner surface of the adjacent side rail *c*, near the edge thereof, and the other flange is similarly secured, as by screws *f f*, to the 40 inner surface of the base or front piece *b*, near the edge of the latter, the corner of this angle-piece or stop *d* being transversely grooved or cut away for the reception of the part *g* of my said leg. This leg is a rod, 45 preferably formed of very stout round wire, comprising an intermediate or body part *g*, an outer part *h* or leg proper at a right angle to the part *g*, and an inner part *i* or arm at a right angle to both of the parts *g h*. Ad- 50 jacent to the stop *d* a block *k* is secured to the base *b*, as by screws *m m*, this block hav-

ing a forwardly-projecting shoulder *j* for engagement at the proper times with the arm part *i*, just named.

The operation of my device will be readily 55 understood from the foregoing description of its construction, taken in connection with the accompanying drawings, the object being to furnish a strong yet simple supporting-leg for the bed when "let down," which leg can 60 be readily and quickly folded and pushed back out of the way and entirely out of sight on the concealed inner side of the base or front piece when the bed is folded or closed, avoiding at the same time any holes in or through 65 either the said front piece or side of the cabinet or the side rails. It will be observed that the angle-plate stops *d* while placed near the free edge of the base or front piece *b* leave sufficient space for the reception of the 70 leg parts *h* when the bed is to be folded, the arm parts *i* then lying close against the inner surfaces of the side rails *c*, as shown in Fig. 5. When the bed is to be let down, the supporting-leg is pulled forward, when the 75 leg part *h* will drop down outside or beyond the base *b* and the arm part *i* will drop down onto the said base *b* between the shouldered block *k j* and the angle-piece stop *d*, as shown best in dotted lines in Fig. 2. Then the 80 supporting-leg is pushed inward until the leg part *h* is against the edge of the base *b* and the arm part *i* beneath the shoulder *j* of the block *k*, as shown in Fig. 3 and in full lines in Fig. 2, all these changes of position 85 requiring but an instant of time and the device being as secure and efficient as it is simple.

Having thus described my invention, what I claim as new, and desire to secure by Letters 90 Patent, is—

1. A leg or support for folding beds, comprising a rod having an intermediate portion, with one end bent at a right angle thereto and the other end bent at a right angle to both 95 the intermediate portion and first-named end, in combination with stops secured to the inner surfaces of the bed for limiting the movement of said leg or support in opposite directions.

2. In a folding bed, the combination with 100 the base or front piece and side rail of the

bed, having a grooved stop, and an adjacent shouldered block secured to the inner surfaces thereof, of a supporting device comprising a rod having an intermediate portion longitudinally movable in said groove, an outer bent end adapted to drop down and form a supporting-leg, when said part is pulled outward and an inner bent end adapted for engagement with said shouldered block, when said part is pushed inward, and the whole supporting device being adapted to be pushed

inward out of sight, when the bed is to be folded.

In testimony that I claim the foregoing I have hereunto set my hand, at Sheboygan, in the county of Sheboygan and State of Wisconsin, in the presence of two witnesses.

PETER CLAY.
